UNITED STATES PATENT OFFICE.

CHARLES C. HANSEN, OF EASTON, PENNSYLVANIA, ASSIGNOR TO INGERSOIL-RAND COMPANY, OF JERSEY CITY, NEW JERSEY, A CORPORATION OF NEW JERSEY.

CORE-DRILL BIT.

Application filed February 1, 1923. Serial No. 616,810.

To all whom it may concern:

Be it known that I, CHARLES C. HANSEN, a citizen of the United States, and a resident of Easton, county of Northampton, State of Pennsylvania, have invented certain Core-Drill Bits, of which the following is a specification accompanied by drawings.

This invention relates to core drills, and particularly to the rotary cutting bits forming a part of such drills. One type of core drill which possesses certain advantages due to its ability to drill holes at any angle is the so-called "diamond drill." This type of core drill is adapted to use black diamonds or carbons as the cutting medium, and these diamonds are usually mounted in the end of the rotary cutting bit. The proper setting of the stones in the end of the bit is a matter of difficulty and it is particularly difficult to properly reset or replace stones which have become loosened or lost.

One object of this invention is to enable the cutting elements of a core drill of the above type to be set in individual cutter pins or mountings, so that comparatively inexpensive chips or small pieces of diamonds may be used and the mountings containing the cutting elements will be detachably secured in the end of the rotary cutting bit. A further object is to position the cutter pins or mountings so that they will perform their work most effectively. A still further and most important object is to firmly secure the cutter pins within the end of the bit against longitudinal or rotative movement by positive locking means which eliminate the use of separate locking or securing devices.

With the above and other objects in view my invention consists in the features of construction and operation set forth in the following specification and illustrated on the accompanying drawing, forming a part hereof.

Figure 1 is a sectional elevation of the bit end of a core drill, showing a preferred form of the present invention;

Figure 2 is a side view, partly in section, of the cutting end of the bit;

Figure 3 is an end face view of the cutting end of the bit;

Figure 4 is an enlarged perspective view of one of the detachable cutter points showing a modification of the securing groove.

Referring to the drawings, I have illus-

trated the bit end of a typical "diamond drill," including a hollow cylindrical core barrel A, one end of which is adapted to be joined to a so-called "calyx" barrel B by a core barrel plug C threaded into the opposing ends of the core barrel and calyx barrel. The other end of the core barrel A is provided with a cylindrical detachable bit D adapted to be threaded to the core barrel A as shown at E. The usual hollow drill rod F is adapted to be threaded in the plug C and the plug C has an axial bore G communicating with the interior of the core barrel A, so that liquid may be forced under pressure through the drill rod F, plug C, core barrel A, and bit D to the cutting end H of the bit D to facilitate the cutting of the core J in a manner which is well known.

The end surface G' of the bit D is provided with a plurality of series of generally longitudinally extending cylindrical holes K, which holes may be located at any suitable angle so that the cylindrical cutters or pins L which are inserted in the holes K may be inclined to the proper degree for satisfactory cutting during the rotation of the bit D. In the present instance the holes K, and hence the cutter pins L have preferably been positioned in three series. In one series indicated at O, the holes K are positioned so that the ends of the cutter pins are located substantially at the center of the end face of the bit, the holes for the cutter pins of this series being preferably parallel with the longitudinal axis of the bit. In the second series, indicated at P, the holes K are inclined diametrically inwardly at an angle to the longitudinal axis of the bit, and in the third series, indicated at Q, the holes are inclined diametrically outwardly at substantially the same angle. The ends of the cutter pins L are provided with the cutting material U, which may be diamond or some other substance, set into the ends of the cutter pins L in any suitable manner.

The cutter pins are each provided with a locking notch R intermediate the length of the pin. This notch R is preferably formed relatively close to the outer end of the cutter pin and may be substantially aligned with the end face of the bit when the cutter pin has been inserted in the hole K, as indicated at R' in Figure 2, or a relatively short distance from the end of the bit as indicated at P² in Figure 2. The notch R may be formed with

straight end surfaces S as shown in Figure 4, or inclined end surfaces T as seen in Figure 2. The cutter pins L are firmly secured in the holes K by driving or forcing the metal of the body of the bit from the end face of the bit at a point V adjacent to the cutter pin into the notches with a chisel W or other suitable tool so that the force of the blow displaces the metal and causes it to flow into the notches and form locking keys. When thus secured the cutter pins are rigidly held against longitudinal and rotative movement. The cutter pins may be removed from the bit when desired by driving a narrow chisel or other small suitably shaped implement alongside the cutter pin L so that the metal holding the pin is chipped off or otherwise removed from the

path of the pin, so that it can be withdrawn and a new one inserted.

20

I claim:

A rotary cutting bit for a core drill, having removable cylindrical cutter pins inserted in longitudinally extending holes in the end face of the bit, each pin having a locking notch intermediate its length, and the metal of the body portion of the bit being driven or forced from the end face of the bit into said locking notches to form locking keys to hold the pins in place and prevent them from turning during operation of the bit.

25

In testimony whereof I have signed this specification.
